UNITED STATES PATENT OFFICE.

EDWARD F. DUDLEY, OF OAK PARK, ILLINOIS, ASSIGNOR TO MIEHLE PRINTING PRESS & MANUFACTURING COMPANY, OF CHICAGO, ILLINOIS, A CORPORATION OF ILLINOIS.

PRINTING-PRESS MECHANISM.

Application filed April 22, 1922. Serial No. 555,952.

To all whom it may concern:

Be it known that I, EDWARD F. DUDLEY, a citizen of the United States, residing at Oak Park, in the county of Cook and State 5 of Illinois, have invented certain new and useful Improvements in Printing-Press Mechanism, of which the following is a specification.

This invention relates to printing presses 10 and more particularly to feeder operating mechanism thereof.

One object of the invention is to provide simple, reliable and efficient operating mechanism for feeding sheets of paper or other 15 material from the stock pile progressively to the printing mechanism.

Another object is to provide driving mechanism for feeding sheets, which mechanism provides for clutching and declutching certain 20 of the motion transmitting parts for accommodating the feeder frame in its normal operative position and in its inoperative position when it is swung away.

Another object is to provide feeder operating mechanism adapted to meet the various requirements for successful commercial use.

These and other objects are accomplished by means of the arrangement disclosed on the accompanying sheets of drawings, in which—

Figure 1 is a fragmentary side elevation of a printing press embodying my invention;

Figure 2 is a fragmentary top plan view of the same printing press;

Figure 3 is a detail sectional view taken in the plane of line 3—3 of Figure 2;

Figure 4 is a detail sectional view taken in the plane of line 4—4 of Figure 3;

Figure 5 is a detail sectional view taken in the plane of line 5—5 of Figure 2;

Figure 6 is a detail sectional view taken in the plane of line 6—6 of Figure 2; and

Figure 7 is a detail view, one part being in section, and taken in the plane of line 7—7 of Figure 6.

The various novel features of the invention will be apparent from the following description and drawings, and will be particularly pointed out in the appended claims.

Referring to the figures of the drawings, it will be noted that I have disclosed my invention in connection with a vertical type of printing press, including a main frame 10

upon which a way-frame 11 is mounted. A 55 feeder frame 12 is pivotally connected by a rod 13 to a bracket 14 secured to the way-frame 11 and to a bracket 15 forming a part of the main frame 10. Rotatably mounted in the main frame 10 and driven from any 60 suitable source is a shaft 16 on which is mounted a disk 17 having a cam race 18 for controlling the movement of oppositely arranged feeder arms 19, only one of which is shown, and which reciprocate between 65 the feed pile 20 and the cylinder of the press, not shown. The arm 19 shown, normally is operatively connected to a crank arm 21 clamped to a rockably mounted member 22. The free end of the crank arm 21 is pivotally 70 connected at 23 to one end of a link 24, the opposite end being connected at 25 to one corner of a triangular shaped frame 26 which is pivotally anchored on a pin 27. In the other corner of the triangular frame 75 26 is a laterally extending roller 28 which moves in the cam race 18 as the disk 17 containing the cam race is rotated. From the mechanism above described, it will be appreciated that as the disk 17 is rotated, 80 the cam race 18 transmits a reciprocatory movement to the feeder arms 19 for carrying sheets of material from the feed pile 20 toward the cylinder of the press. It is desirable at the time of make-ready and at 85 other times to swing the feeder frame on its pivotal shaft 13 away from its normal operative position. To do this, it is necessary to provide a special separable connection between parts of the operating mechanism 90 carried by the main frame structure and the feeder frame.

Referring particularly to Figures 3 and 4, it will be noted that the member 22 has a pocket 29 containing a spring 30 which 95 presses forwardly a tongue 31 or one part of a clutch which is mounted upon a stem 32 against which the spring 30 presses. Cooperating with the tongue 31 is a second clutch or grooved member 33 which receives 100 the tongue and which is secured to a shaft 34 by a key 35. One end of the shaft 34 has a groove aligned with that of the grooved member 33 to complete said second clutch member. Secured to the shaft 34 is 105 the feeder arm 19, so that it is seen that there is a releasable clutch connection between the shaft 34 on which the feeder arm is

mounted and the driving member 22 which receives its motion from the cam 18.

In addition to the suction gripper means 36 carried by the arms 19 having a swinging movement with said arms, such suction means is given a dipping action to pass downwardly into engagement with the top sheet of material. Such dipping action is controlled from a cam 37 formed on the exterior rim of the disk 17. Riding upon this cam 37 is a roller 38 mounted in one end of the arm 39 of a bell crank lever 40 having the pin 27 as its pivotal center, the other arm 41 of the bell crank lever having pivotally connected thereto one end of a link 42, the other end of which is pivotally connected at 43 to a collar 44 loosely mounted over the flanged head portion 45 of the member 22. Pivotally connected to an intermediate portion of the bell crank lever arm 41 is a rod 46 around which is mounted a coiled spring 47 which yieldably holds the roller 38 in engagement with the cam 37. It is apparent, therefore, that as the cam disk 17 is rotated the collar member 44 is given a rotary oscillatory movement about the member 22 as a center. This motion is transmitted to the suction gripper shoes 36 for causing the latter to dip into engagement with the top sheet of material in the pile 20 and for lifting same preparatory to being fed progressively away from the feed pile. The collar 44 forms one part of a clutch. The other part takes the form 35 of a collar 48 which is loosely rotatably mounted upon the member 33. The collar 48 is provided with a projecting pin 49 (see Figures 5, 6 and 7) which passes into an opening 50 in the collar 44 whereby the parts are locked together. Preferably surrounding the shank of the pin 49 is a spring 51 for permitting the pin 49 to move rearwardly if the same should engage a part other than the opening 50 of the collar 44. 40 These parts, however, normally register with respect to each other when swung around into position, but in any event after they are swung into position with respect to each other they may be given a slight relative rotative movement for bringing the pin 49 and opening 50 into register if they are not in register at the time of bringing the collars 44 and 48 together. It will be understood that the clutch parts 44 and 48 are separated from each other when the feeder frame and its bracket 12 are swung away from the main frame as indicated in dotted lines in Figure 2. Upon such rearward swinging movement of the feeder frame and its bracket 12, not only is the clutch part 48 swung away from the clutch part 44 for disconnecting the members which transmit a dipping movement to the suction gripper 36, but also the clutch member 33 is withdrawn from the clutch mem-

ber 31 for disconnecting the parts which normally transmit the oscillatory movement to the feeder arms 19.

Following the connection from the clutch member 44 to the suction gripper 36 it will be noted that formed integrally with the collar clutch member 48 is a bracket 52 having a cam groove 53 therein in which a roller 54 rides. This roller is mounted upon a lever 55 pivoted upon a stationary support 56 located at one side of the bracket 52. To the opposite end of the lever 55 is pivotally connected a connecting rod 57, the upper end of said connecting rod being pivotally connected to an arm 58 secured to a pin 59 rotatably carried in a bearing portion 60 at the upper end of the transfer arm 19. Secured to the opposite end of the pin 59 is an arm 61 which is connected to the suction shoe unit 36. It is apparent, therefore, that as the roller 54 rides to and fro in the cam race 53 as the bracket 52 is oscillated, that the suction gripper unit 36 will be dipped into engagement with the top sheet of paper and then be raised out of engagement with the pile for the purpose stated.

A spring 62 surrounding the rod 57 is adapted to assist in giving the suction gripper 36 its dipping action down into engagement with the top sheet of material. In this connection, it will be understood that when the rod 57 is in its lowermost position on the arm 19, the spring 62 is compressed, so that as the cam 53 causes the rod 57 to rise to give dipping action to the gripper 36, the spring 62 assists in making the action more positive. A spring 63 is employed for yieldably holding the bracket 52 and, accordingly, the collar 48 in the limit position, shown particularly in Figure 1.

It is my intention to cover all modifications of the invention falling within the spirit and scope of the following claims.

I claim:

1. In a printing press, the combination of two pivotally connected frame members, a shaft carried by one of said frame members, cooperating rockably mounted clutch members, one carried by each of said frame members and one carried by said shaft, a feeder arm secured to said shaft and movable with one of said frame members and through said shaft secured to one of said clutch members, and driving means for said feeder arm carried by the other frame member and operatively connected to said other clutch member, said feeder arm and its driving mechanism being releasably connected through said clutch members whereby said feeder arm may be moved out of operative association with its driving means when one frame member is moved with respect to the other.

2. In a printing press, the combination of

- a plurality of relatively movable frame members, a shaft carried by one of said frame members, cooperating movably mounted clutch members, one carried by each of said frame members and one carried by said shaft, a feeder member secured to said shaft and carried by one of said frame members and through said shaft secured to one of said clutch members, driving means for said feeder member carried by the other frame member and operatively connected to said other clutch member, said feeder member and driving means being releasably connected through said clutch members whereby the same may be disconnected when one frame is given a certain relative movement with respect to the other.
3. In a printing press, the combination of a plurality of relatively movable frame members, a shaft carried by one of said frame members, cooperating movably mounted clutch members, one carried by each of said frame members and one by said shaft, a feeder member secured to said shaft and carried by one of said frame members and through said shaft secured to one of said clutch members, driving means for said feeder member carried by the other frame member and operatively connected to said other clutch member, said feeder member and driving means being releasably connected through said clutch members whereby the same may be disconnected when one frame is given a certain relative movement with respect to the other, and means including said clutch members for assuring said feeder member and its driving means being operatively connected after separation so that the feeder mechanism and the other parts of the press are in proper time relationship.
4. In a printing press, the combination of a plurality of relatively movable frame members, a shaft carried by one of said frame members, aligned cooperating clutch members, one carried by each of said frame members and one by said shaft, a feeder member mounted on said shaft and carried by one of said frame members and secured to one of said clutch members through said shaft, driving means for said feeder member carried by the other frame member and operatively connected to said other clutch member, said feeder member and driving means being releasably connected through said clutch members whereby the same may be disconnected when one frame is given a certain relative movement with respect to the other, and yieldable means including said clutch members for assuring said feeder member and driving means being connected after separation so that the feeder mechanism and the other parts of the press are in proper time relationship.
5. In a printing press, the combination of a plurality of frame members having a relative movement with respect to each other, feeder means carried by one of said frame members, driving means therefor carried by another one of said frame members, and means for releasably connecting said feeder means and driving means comprising cooperating clutch members, one of which is yieldably carried by one of said frame members whereby said clutch member may yield in the event that it is not in proper registering position with respect to its cooperating clutch member when pressed into engagement therewith, said feeder means being carried by said other clutch member.
6. In a printing press, the combination of a stationary frame member, a frame member pivotally mounted on said stationary frame member, a shaft carried by said pivotally mounted frame member, a feeder arm carried by said shaft, driving means associated with said stationary frame member for driving said feeder arm, and oscillatory clutch means forming a separable connection between said feeder arm and driving means comprising a clutch member carried by said stationary frame and a cooperating clutch member carried by said shaft.
7. In a printing press, the combination of a stationary frame member, a frame member pivotally mounted on said stationary frame member, a shaft carried by said pivotally mounted frame member, a feeder arm carried by said shaft, driving means associated with said stationary frame member for driving said feeder arm, clutch means forming a separable connection between said feeder arm and driving means comprising a clutch member carried by said stationary frame and a cooperating clutch member carried by said shaft and carrying said feeder arm, and means whereby said clutch members may move into driving relationship with respect to each other only when the feeder arm and the other parts of the press are in proper time relationship.
8. In a printing press, the combination of relatively movable frame members, a feeder arm carried by one of said frame members, driving means for said feeder arm associated with said other frame member, and a releasable connection between said feeder arm and its driving means comprising a yieldably mounted clutch member carried by one of said frame members and another clutch member carried by the other of said frame members and carrying said feeder arm.
10. In a printing press, the combination of a plurality of relatively movable frame members, feeder means carried by one of said frame members, driving mechanism associated with another of said frame members for giving such feeder means a plurality of operative movements of different character, and two separable connections between said feeder means and driving mecha-

nism whereby the same may be disconnected when one frame member is moved relative to the other.

10. In a printing press, the combination of a plurality of relatively movable frame members, a feeder arm carried by one of said frame members, gripper means carried by said feeder arm and having a dipping action, means for actuating said feeder arm and giving said gripper a dipping action, and two separable connections between said driving means and said feeder arm and gripper means whereby said parts may be moved out of operative relationship when one frame member is moved relative to the other.

11. In a printing press, the combination of a plurality of relatively movable frame members, a feeder arm carried by one of said

frame members, gripper means carried by said feeder arm and having a dipping action, means for actuating said feeder arm and for giving said gripper a dipping action, a plurality of separable connections between said driving means and said feeder arm and gripper means whereby said parts may be moved out of operative relationship when one frame member is moved relative to the other, and means whereby when said frames are moved back into operative relationship the connection between the feeder arms, gripper means and driving means for same will be properly established in time relationship.

Signed at Chicago, Illinois, this 17th day of April, 1922.

EDWARD F. DUDLEY.
